ADJUSTABLE CHOKE NIPPLE

Filed Dec. 26, 1931

FIG. 1.

FIG. 2.

FIG. 3.

FIG. 4.

James F. McKaig.

INVENTOR

UNITED STATES PATENT OFFICE

JESSE F. MCKAIG, OF OKLAHOMA CITY, OKLAHOMA

ADJUSTABLE CHOKE NIPPLE

Application filed December 26, 1931. Serial No. 583,267.

My invention relates to improvements in adjustable choke nipple especially adapted for use with high pressure oil and gas wells.

The principal objects of my invention are to provide a device of this character which is positive in action, simple and inexpensive in construction; new, novel and easily operated; which is strong, durable, reliable and of evident utility; which cannot easily get out of order and is efficient for the purposes for which it is intended; to provide a choke nipple adapted to be inserted in the plug gauge hole in the master gate valve of an oil well and constitute a flow nipple for the daily allowable potential of a well under proration; to provide a device which will completely close or allow complete opening for the allowable flow of the well without changing any of the connections; to provide a device which will conserve the gas by keeping the well flowing steadily without any extra volume of gas forming against the master gate valve; to provide a device which will permit the taking of the well's potential by opening the master gate valve only, without any change or the use of any other connections or extra labor; to provide a device which will give added safety against sand cutting in high pressure wells when flowing the allowable daily potential by virtue of the fact that the oil flow is taken indirectly from the side and below the gate of one of the master gates, thus confining the high pressure below the top of the master gate while having two of said gates closed when four master gates are used; to provide a flow nipple for taking the daily allowable potential through the plug gauge hole in the master gate as stated, and regulating the said flow by adjustment of means inside the choke nipple by controlling means from the outside without any change of connection, thus flowing the daily allowable potential in a small, steady stream for twenty-four hours per day instead of taking the said allowable potential by opening the master gate and flowing the well unrestrained in three or four hours; to provide an adjustable choke nipple in which the pressure from the flow of the well will strike the control from the side instead of from the end and

thus take the pressure indirectly out of the line of flow; to provide a device which will act as a safety blow-off for high pressure oil and gas wells and restrict the flow to a small steady stream, thereby producing a higher gravity oil. 55

With these and other objects in view my invention consists of the construction, novel features and combination of parts herein-after more fully described, illustrated in the accompanying one-sheet drawing and pointed out in the claims hereto appended. Various changes in the form, proportion, size, shape, weight and minor details of construction, within the scope of my invention may be resorted to without departing from the spirit or broad principle of my invention or yielding any of its benefits. 60 65

In the accompanying drawing, Figure 1 is a side elevation of the device, Fig. 2 is an elevational view showing the device installed in a master gate valve, Fig. 3 is a sectional elevation and Fig. 4 is a fragmentary sectional view of the T connection and plug. 70 75

In the following description like reference numbers designate like parts in all the figures, and it is to be understood that the drawing is to be interpreted as being illustrative and not restrictive. 80

The oil and gas producing States are seeking to conserve the oil and gas and prevent waste. One of the recommendations now proposed is to require all producing wells to produce through a choke having an area of opening of limited size. This device is now usually in the form of a flow bean having a valve adjustment the maximum opening being about three inches in diameter. In installing this device it is placed on the casing above the master gates in the main line connection to the separator and this usually requires disconnecting and removing the sand trap which involves considerable time and labor. The flow through this device is taken directly from the casing under full pressure from the well and is choked down by means of the valve. The sand cutting soon changes the orifice size and no positive control is possible. When it is necessary to take a new open flow potential of the well to figure the 85 90 95 100

prorated allowable flow, the flow bean must be removed, the sand trap replaced before the master gates can safely be opened and this requires time, trouble and labor.

5 With my improved adjustable choke nipple, all that is necessary to install the same is to remove the drain plug or gauge hole plug in the side of the master gate and replace the same with my choke nipple. This requires 10 only a few minutes of time and very little labor. The device is connected to a small separate pipe running to the separator, and this pipe and nipple connection are left undisturbed when the master gates are opened for 15 taking the potential and the production flows through the sand trap and into the separator.

One embodiment of my invention is shown as follows: Nipple 1 having longitudinal bore 2 is provided with threads 3 for screwing into 20 drain plug hole 3—a in master gate valve 4 as seen in Fig. 2. Threads 6 on nipple 1 connect with pipe T 23. Control stem 7 is seated in packing body housing 8 and is provided with hand operating wheel 9. Nipple 1 is 25 enlarged at 10 to allow for an ample threaded socket 11 for seating the threaded end 12 of housing 8. Fine interior threads 13 in member 8 co-act with the fine exterior threads 14 near the lower end of stem 7 to hold said 30 stem in any desired position. Packing gland nut 15 is threaded at 16 to the upper end of packing body housing 8. Packing gland 17 under pressure of nut 15 holds the packing 35 18 securely around the stem 7. A shoulder 19 within gland 17 is formed by an enlargement 40 of the stem 7. The stem 7 terminates in a rounded lower end 20 which seats, when in closed position, in the seat 21 formed below the bore 2 of nipple 1. The smooth cylindrical end 22 of stem 7 is of larger diameter than bore 2 of nipple 1 and seat 21 is of sufficient 45 depth so that the said bore 2 is completely closed when stem 7 is fully seated. The position of shoulder 19 on stem 7 is such that the 50 said shoulder forms a stop against gland nut 15 when the end 22 of said stem 7 is unscrewed out of seat 21 and bore 2. Threads 6 serve for connecting nipple 1 to pipe T 23. Sand impinging plug 24 is screwed into T 23, as best 55 seen in Fig. 4, so as to receive any sand cutting action from the flow of oil and gas passing through bore 2 of nipple 1. Flow pipe 25 leading to the separator is screwed into the side opening of T 23. Pressure gauge 26 is connected by pipe 27 to the master gas valve 5. Nipple 1 is connected to the valve 4 under gas 28 and gauge 26 in like manner is connected under gate 29 of valve 5.

Deep wells producing from 6500 feet develop rock pressure up to 2200 pounds per square inch. Four master gate valves are usually installed to guard against any possibility of the well getting out of control. The upper two of these valves, 4 and 5 are shown 65 in Fig. 2. My nipple 1 may be seated in valve

5, replacing gauge 26 in which event both valves 4 and 5 may be closed while the allowable potential of the well may flow through my choke nipple. In the interests of conservation, engineers, and geologists recommend, 70 where proration is practiced, that all large wells shall, except when taking potentials, produce through a choke of limited size. The proration laws limit the flow of even large producers to a few hundred barrels of oil per 75 day. This daily allowable flow can be produced in a very short time through a large pipe and then the well must be closed down. Large, expensive flow beans are being used 80 as chokes but their installation requires the removal of the sand trap, a fragment of which is shown at 30 in Fig. 2. Then when it is necessary to take a potential of the well the sand trap and its connections must be replaced. This involves labor expense in addition to the cost of the flow bean.

I have been using my simple, inexpensive choke nipple on a well for some time. With a bore 2 of only three-eighths of an inch and control stem 7 open only five turns of the 90 fine threads 14 to about one-third of the bore openings, the nipple has flowed about 500 barrels in 24 hours at 1500 pounds pressure. Such a small stream of oil flowing from the drain plug opening in the side of the master 95 gate valve carries very little sand. The little cutting action that is caused by the sand is directed against the sand impinging plug 24. After flowing several thousand barrels of oil plug 24 showed some wear and was replaced with a new one at very little expense. No appreciable wear could be detected in 100 nipple 1 after flowing 90,000 barrels. This small stream of oil flowing steadily conserves the gas, prevents any extra volume of gas 105 forming against the master gate valve and produces a higher gravity oil.

From this description it will be seen that I have produced an efficient, inexpensive, adjustable choke which can be installed quickly 110 and easily without making any structural changes in the valves or piping, a device which requires no change in connections for its operation and which becomes a permanent part of the well's equipment without interfering 115 with the normal operation of the other necessary equipment. While I have used for illustration a definite size of bore it is to be understood that other sizes may be made for specific installations.

Having thus described my invention what I claim as new and desire to secure by Letters Patent is:

1. In an adjustable choke nipple, a nipple having a central bore, an enlarged section on the said nipple having a threaded socket; a packing body housing having a central bore for threaded connection in said socket and having fine internal threads in the bottom of said bore; a control stem in the said housing, 125

having an enlarged lower portion with fine external threads spaced from its lower extremity for co-acting with the internal threads of the said housing; a smooth cylindrical terminus on the said stem below the said external threads, the said terminus having a larger diameter than that of the central bore of said nipple, the said enlarged section of the nipple having a 5 seat for the said terminus below the bore of the said nipple and in the axis of the said stem; a reduced section on the said stem provided with a hand wheel; a stuffing box on the said housing for the control stem, the shoulder formed between the small and large portions of the stem providing, stop means to limit the upward movement thereof.

2. In a device of the class described, in combination, a choke nipple for seating in the 20 drain plug hole of a master gate valve and having a central bore; a control stem of larger diameter than the said bore with its axis in the same plane as that of the bore but at right angles thereto for adjusting the flow 25 of liquid through the said bore; an enlarged section on the said nipple having a seat for the end of the said stem below the said bore; a housing and stuffing box for the said stem in threaded connection with the said enlarged 30 section above the said bore; means on the said stem for adjustably positioning the lower end thereof within or across the said bore; a pipe T fitting in threaded connection with the said nipple; a sand impinging plug seated in said 35 T on the axis of the said bore and a flow pipe connected to the side opening of the said T.

In testimony whereof I hereunto affix my signature.

JESSE F. McKAIG.
